Hannibal E. Miller.
Inventor

William Dymon

Attorney

UNITED STATES PATENT OFFICE.

HANNIBAL E. MILLER, OF CHARLOTTE, NORTH CAROLINA.

CUTLERY.

Application filed October 10, 1925. Serial No. 61,762.

My invention relates to improvements in cutlery and is particularly adapted to knives, forks and other tableware although not necessarily restricted to this use.

5 An important object of my invention is to provide a device of the above mentioned character with improved means for retaining the blade or the like in its handle.

10 Another object of my invention is the provision of a new process for the manufacture of cutlery.

15 A further object of my invention is to provide an article of cutlery having its blade capable of ready removal and replacement.

20 Yet another object of my invention is the provision of a device of this character which will withstand long periods of hard usage, sterilizing and the like, without coming apart.

25 Other objects and advantages of my invention will be apparent during the course of the following description.

30 In the accompanying drawings, which form a part of this specification and wherein like characters of reference denote like or corresponding parts throughout the same,

35 Figure 1 is a side elevation, parts being broken away, of an article of cutlery embodying my invention.

Figure 2 is a similar view of the handle, showing the pattern in operative position and ready for the pouring of the metal,

40 Figure 3 is an edge elevation of the pattern,

45 Figure 4 is a top plan view thereof,

Figure 5 is a side elevation of the removable tang,

50 Figure 6 is a similar view of a modified form of tang which is not removable, and,

Figure 7 is a similar view of a modified form of removable tang.

55 In the drawings, wherein for the purpose of illustration is shown a preferred embodiment of my invention, the numeral 10 designates the handle shell formed from silver or any other suitable or desirable material, said shell having its blade receiving end open. A pattern plate 11 has a metal tang 12 adapted to project into the shell, substantially centrally thereof, said tang having its sides tapered towards its lower end,

60 and being provided with a cut out portion 13, generally V-shaped, which forms a spring arm 14 on one side of the tang, said

arm being free at its upper end, said upper end being bevelled inwardly as shown at 15. The cut out portion 13 is filled with a compressible material 16, such as cork, and a generally U-shaped clasp or catch 17, having one of its arms arranged at an angle corresponding to the angle of the bevel on the end of the arm 14, is arranged about the tang, one of its arms bearing against one side of the tang, and the other arm engaging the bevelled end of the spring arm 14 to 65 retain the same in position.

60 A collar 18 surrounds the upper portion of the tang and has a reduced lower end which fits into the upper end of the shell 10 to be filled. A pouring funnel 19 is secured to the plate 11 and aligns with an opening 20 in the collar, said opening communicating with the interior of the shell. A smaller opening 21 is arranged on the 70 opposite side of the collar, which also communicates with the shell, said opening serving as a vent.

75 Any suitable metal 22 is then poured into the funnel, fills the shell, and surrounds the pattern tang, the clasp or catch 17 becoming embedded in the metal. If preferred, a light substance may be poured into the lower end of the shell, such as plaster of Paris, as illustrated at 23. When the metal has cooled, the pattern may be removed, the spring arm 80 14 being pressed into the space 13 by the cam action of the angled arm of the catch 17, the cork being capable of giving enough for this operation. The cork prevents the metal from filling in the opening 13 and 85 preventing the removal of the tang.

90 When the pattern has been removed, the blade 23' is inserted, the tang of the blade corresponding with the tang of the pattern. The collar 24 of the blade corresponds with 95 the collar 18 of the pattern but it has no openings, and its reduced end which fits into the shell is shorter than that of the collar 18, the additional space being filled by a cork washer 25 which prevents water 100 from entering the shell.

105 It will be seen that the blade may be removed or replaced at will, the spring arm 14 having sufficient tension to hold the blade in place under ordinary pressure, but having sufficient resilience to allow removal of the blade when such removal is desired. If desired, the opening 13 in the blade may

be filled with cork as shown in Figure 7, and if it is desired that the blade be immovably held in place, the end of the spring arm is bevelled in the opposite direction as shown at 26 in Figure 6.

While I have shown and described the preferred embodiment of my invention, it is to be understood that various changes in size, shape, and arrangement of parts may 10 be resorted to without departing from the spirit of my invention or the scope of the subjoined claims.

Having herein described my invention, what I claim and desire to protect by Letters Patent is:

1. A pattern for forming a handle for cutlery, said pattern comprising a plate, a tang adapted to be inserted in the shell of the handle, said tang having a spring arm spaced from the body portion of the tang, means to allow metal to be poured around the tang, means to prevent the metal from filling the space between the spring arm and the body portion of the tang, and means 25 to allow removal of the tang from the handle when the metal has cooled.

2. A pattern for forming a handle for cutlery comprising a tang adapted to be inserted in the handle, means to pour metal 30 into the handle shell around the tang, means to prevent the metal from locking the tang in the handle, means normally holding the tang within the handle, and means whereby

the tang may be dislodged without destroying the handle filling.

3. A pattern for forming a handle for cutlery, said handle comprising a plate, a tang adapted to be inserted in the shell of the handle, said tang having its sides tapered, and having a portion of its body 40 portion cut away to form a spring arm spaced from the body portion, said arm having its end bevelled, a collar on said tang surrounding its end adjacent the plate, said collar having a pouring hole and a vent, a 45 funnel carried by the plate and communicating with the pouring hole, said pouring hole communicating with the interior of the shell, whereby metal may be poured into the shell around said tang, a clasp carried 50 by said tang and engaging the bevelled end of the spring arm, and adapted to be embedded in the metal when it cools, and a compressible filling in the cutaway portion of the tang.

4. A pattern for forming a handle for cutlery, said pattern comprising a body member, a tang on said body member said tang tapering towards its end and being cut away to form a spring arm having an 60 inwardly bevelled end, and a catch on said handle adapted to engage the bevelled end of the spring arm and removably secure the tang in the handle.

In testimony whereof I affix my signature.

HANNIBAL E. MILLER.
